UNITED STATES PATENT OFFICE

WILLIAM C. HOLBROOK, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed July 30, 1927. Serial No. 209,559.

This invention relates to refrigerating apparatus, particularly to devices such as hinges, latches, escutcheons, and the like which are ordinarily associated with the doors of refrigerating cabinets.

It is among the objects of the invention to provide an improved construction of hinge or the like which is economical to manufacture, which has an attractive appearance and which is stronger and more durable than devices of this sort heretofore used.

It is another object of this invention to provide a hinge or similar device which may be attached to highly finished or frangible surfaces without injuring the finish of the surface.

It is also an object of this invention to provide a pressed metal hinge or similar device which is economical to manufacture and which has the rich, heavy appearance of cast metal devices of this character and a strength and durability superior to cast devices.

Further objects and advantages of the present invention will be apparent from the following description, reference being had to the accompanying drawings, wherein a preferred form of embodiment of the present invention is clearly shown.

In the drawings

Fig. 1 is a perspective view of a hinge; Fig. 2 is a view of a hinge partly in longitudinal section and partly in elevation, and

Fig. 3 is a section on the line 3—3 of Fig. 1.

Referring to the drawings, 10 indicates a door of a refrigerating cabinet which is supported on a jamb 11 by hinges generally denoted by 12. The door includes a metal cover having a frangible finish thereon and formed to provide the front surface 13 and edge surface 14. The hinge chosen for illustration of the present invention has a butt member 15 attached to the jamb and a strap member 16 suitably pivoted to the butt member in the usual manner and attached to the door. For the sake of appearance it is desirable to have the strap member in contact with both surfaces of the door and to this end it is provided with an L-shaped edge which contacts with both surfaces.

Hinges of this character as heretofore con-

structed have frequently been made of cast metal having an outer curved surface 20 which presents a rich and pleasing appearance and a flat surface to be clamped against the door. The flat surface has a large area which distributes the clamping force uniformly over the contacting surface, which results in a low pressure being applied to the base or frangible surface. These hinges have been objectionable for the reason that in cases where the hinge is in contact with both the face and edge surface of the door, unless the strap member is made so massive as to be objectionable from the standpoint of cost and appearance, the strap member is particularly weak at the point opposite the corner 21 and frequently breaks at this point when the door is swung wide open and suddenly stopped by the hinge reaching the limit of its travel.

I remedy the above defects by providing a hinge having a strap of pressed metal which on the outside may have an appearance identical with that of previously known cast hinges, the strap member being appropriately curved as shown in the sectional views. The curvature of the strap provides great strength and results in having the strap in contact with the surface of the door at its edges only. In order to provide great strength at the portion of the strap which passes around the corner of the door and also to provide an edge which will not injure the finish of the door surface, I provide a reinforcing rim or flange 22, integral with the strap and continuous throughout the length of the edge which contacts with the door. This flange is formed preferably by turning the edges of the strap in along its entire length. Thus the strap has in effect an L-shaped edge, one leg of which contacts with the surface of the door and both legs of which are provided with a reinforcing and surface protecting bend, flange or rim. The fact that the rim is continuous around the corner makes an exceedingly strong hinge.

It has been found that the best results are obtained when the rim makes contact with the surface of the door at a very slight acute angle, preferably about 3°. In this case the

edge in contact with the door is blunt enough not to injure the surface, and the edge of the metal, which in the case of drawn pressed articles is ordinarily sharp and jagged, out of contact with the surface.

It will be understood that whether the butt member 15 is to be attached to a surface which may be injured by drawn or sharp edges, it may also be formed in the manner of the strap. It will also be understood that the invention is not limited to a hinge, but is equally applicable to structures such as latches, escutcheons, handles and similar devices, the hinge having been selected for the sake of illustration only.

While the form of embodiment of the present invention as herein disclosed, constitutes a preferred form, it is to be understood that other forms might be adopted, all coming within the scope of the claim which follows.

What is claimed is as follows:

In a pressed metal hinge for refrigerating cabinets, a member having an L-shaped edge adapted to be mounted on a frangible base, said member having a bent flange forming a convex surface contacting the base, the marginal edge portion of the flange extending away from and out of contact with the base so as to prevent breakage of the frangible base at the contacting point of the bend with the base, whereby substantially no mars are made on the base by said contacting portion.

In testimony whereof I hereto affix my signature,

WILLIAM C. HOLBROOK.
